UNITED STATES PATENT OFFICE

VANN MARS LIGON, OF WICHITA FALLS, TEXAS, ASSIGNOR, BY DIRECT AND MESNE ASSIGNMENTS, OF TWO-THIRDS TO BERT LESTER LIGON, OF WICHITA FALLS, TEXAS, AND ONE-THIRD TO C. W. BOLLER, OF WICHITA FALLS, TEXAS

WELL SWAB

Application filed April 29, 1929. Serial No. 358,822.

My invention relates to swabs for use in raising liquid from deep wells, such as oil, water, and gas wells.

This type of swab is adapted particularly for use in cleaning out a well after it has been drilled and preparatory for bringing the well into production. The use of the device is not restricted to this purpose, however, and may be used generally wherever it is desired 10 to swab a well.

In the ordinary swab now used for the purposes indicated difficulty is experienced in introducing the swab rapidly into the well. It is most common to suspend the swab 15 at the lower end of a cable or line and drop the same by its own weight to the proper level beneath the liquid in the well and then draw it upwardly to the surface with the load of liquid above it. Valve controlled passages 20 may be provided to allow the liquid in the well to pass upwardly thru the swab as it sinks beneath the surface of the liquid. The outer edge of the swab rubber usually rubs against the wall of the casing and not only 25 impedes the speed with which the swab may drop but also wears the rubber materially so that it has to be frequently replaced.

It is an object of my invention to provide a swab having a rubber or packing member 30 which is adapted to collapse materially during its downward stroke to allow the liquid to pass around the outside of the swab, thereby increasing the speed of travel and preventing wear upon the packing member.

I also desire to provide a packing member 35 which is strong in construction but easily installed upon the swab and which is convenient to change when replacement is desired.

In the drawings herewith, Fig. 1 is a side view partly in central vertical section illustrating the construction of my swab.

Fig. 2 is a central vertical section thru the lower end of the mandrel of the swab showing the valve which may be employed.

Fig. 3 is a side view partly in elevation and partly in section illustrating a connection which may be employed between my swab and the operating device.

Fig. 4 is a broken view in central vertical section showing the swab in expanded

position, such as is assumed on the upward stroke.

Fig. 5 is a transverse section thru the cup taken on the line 5—5 of Fig. 1.

Fig. 6 is a similar section taken on the plane 6—6 of Fig. 1.

My swab may, of course, be employed either with rotary or the standard system of drilling and may be suspended upon a pipe or rod or may be connected with the lower end of an operating cable. In Fig. 1, I have shown the device as adapted for connection with a cable or wire line by means of which it may be raised or lowered in the well. For this purpose there is a nipple 1 having a shank 2 at 60 the upper end which may be provided with circumferential grooves or serrations 3, with which a fishing tool or spear may be engaged in case of emergency. A central passage 4 thru the nipple provides a passage for the 65 cable 5, which has a swivel connection with the nipple by means of a block 6 at its lower end within which the cable is expanded and soldered.

The said head 6 fits within a recess 7 in the 75 nipple and may rotate relative thereto. The lower end of the nipple is threaded at 8 for engagement with the upper end of the mandrel 9 upon which the swab is mounted. A plurality of lock nuts 10 are shown at the 80 connection between the mandrel and the nipple 1 to assure against unscrewing of the said connection.

The mandrel 9 is a cylindrical bar of steel, the lower end of which has been bored centrally to provide a chamber indicated at 11 in Figs. 2 and 4. The mandrel is threaded at its lower end into engagement with a valve chamber 12 having a valve seat 13 secured to the lower end thereof by means of cap screws 14. The said valve seat is tapered inwardly and downwardly and receives a valve 15 shaped to engage therein and having a packing member 16 thereon. A downwardly extending stem 17 on the valve has the usual 90 dart 19 at its lower end to engage with the bottom of the well to unseat the valve when desired.

The mandrel 9 has openings from the central chamber 11 at the lower end, said open- 100

ings 20 being formed to open into the interior of the swab cup 21. Said swab cup is preferably of rubber or other similar flexible composition constructed to resist wear in the operation of the swab. It is of approximately cylindrical shape having cylindrical walls 22 to engage with the side of the casing. The upper end of the cup is decreased slightly in outer diameter to engage within a retaining plate or ring 23. The lower end of the cup is curved inwardly and has its lower end somewhat wedge-shaped in cross section, as shown at 24 in Figs. 1 and 4.

As a support for said swab I provide a ring 25 of metal which may be welded to the outer wall of the mandrel, said ring extending laterally from the mandrel and in supporting engagement with the swab cup. The upper side of the said ring is provided with a V-shaped groove 26 into which the wedge-shaped lower end of the swab may engage. The inner side of the said V-shaped groove 26 is inclined upwardly to provide a tapered seat 27 upon which the inner side of the cup 21 may engage.

It is to be noted that the swab rubber or cup 21 is slightly shorter in length than is the distance between the ring 23 and the seat 27, thus allowing a sufficient amount of play of the cup in its seat so that it may move upwardly into the position shown in Fig. 1, thus allowing the side walls of the cup to collapse inwardly away from the casing. It will be seen that when in this collapsed position the lower supporting ring 25, by means of the tapered face 27, allows the resilient cup to contract as it moves upward. This contraction brings the outer wall 22 of the cup inside the outer circumference of the ring 25 and thus serves to space the cup slightly from the wall of the casing while it is going into the well and thus prevent injury to the cup. The upper plate or ring 23 has a plurality of openings 28 therein whereby liquid from above the cup may find access to the interior thereof.

I have shown the mandrel as provided with a diametrical opening 30, thru which a pin or bar may be extended to hold the mandrel 30 while it is being screwed into connection with the nipple 1 of the valve chamber 12, this transverse passage being above the upper end of the chamber 11, as will be noted from Fig. 4.

In Fig. 3 I have indicated a connection which may be made with the upper end of the mandrel, and a nipple 33 which may be engaged with a drill stem or with some rigid operating means whereby the swab may be operated in the well.

In the use of my device the swab may be secured upon an operating cable, as shown in Fig. 1, and dropped downwardly into the liquid in the well. It is to be understood that the swab drops very rapidly in its descent to

the desired position at the lower end of the well or beneath the level of the liquid which is to be raised to the surface. In its downward descent the cup collapses into the position shown in Fig. 1. It is moved upwardly into contact with the supporting plate 23 and the lower end is moved inwardly out of contact with the casing. This allows the liquid to pass upwardly between the swab and the casing and, of course, further liquid may pass upwardly past the valve 15 and out thru the openings 20 and 28. When the proper level has been reached the swab will be raised upwardly and the load of liquid will be trapped above the same thru the closing of the valve 15, and the expanding of the cup 21. The load of liquid above the cup will exert a pressure thru the openings 28 to the interior of the cup, forcing it downwardly into its seat upon the ring 25 and expanding the walls against the casing, as shown in Fig. 4. The load of liquid above the swab may then be raised to the surface.

It will be noted that as the cup is moved downwardly upon the conical surface 27 it is also expanded toward the casing, thus assisting the outward pressure of the liquid in maintaining a seal of the cup with the inner wall of the casing.

The advantage of this device lies largely in the construction and mounting of the swab cup. The slideable manner in which the cup is mounted upon its support allows it to collapse in a most effective manner to greatly increase the speed of operation, due to the freer passage of liquid about the cup, and also greatly prolonging the life of the cup, due to the freedom of contact between the cup and the casing during its descent into the well. It is particularly desirable to prevent contact between the cup and the casing during its downward movement, due to the fact that it is moving at such a high rate of speed during its descent that if it were allowed to rub against the casing it would heat up thru friction and the rubber or other composition of which it is made would rapidly deteriorate and the cup would soon be destroyed. It has been found to be a great advantage and is considered a valuable feature of my invention that the cup is prevented from contacting with the casing in its descent.

I claim:

1. A swab including a mandrel, a supporting ring thereon, a flexible cup on said ring, a retaining plate on said mandrel to support the upper end of said cup, said cup having a longitudinal movement between said plate and said ring.

2. A swab including a mandrel, a cup of flexible material on said mandrel, a seat for the lower end of said cup, and means to restrain the outward movement of the upper end of said cup, said cup being slideable between said seat and said restraining means.

3. A swab including a mandrel, a cup of flexible material on said mandrel, a seat for the lower end of said cup, and means to restrain the outward movement of the upper end of said cup, said cup being slidable between said seat and said restraining means, said seat being beveled downwardly and outwardly to expand said cup when it moves downwardly thereon.
4. A swab including a mandrel, a cup of flexible material thereon, said cup having a longitudinal movement on said mandrel and means to move the walls of said cup radially during the downward movement thereof.
5. A swab including a mandrel, a cup of flexible material thereon, said cup having a longitudinal movement on said mandrel, and means to limit said movement downwardly, said means acting to expand said cup.
6. A swab including a mandrel, a supporting ring thereon, a cup of flexible material slidable on said mandrel and adapted to seat on said ring.
7. A swab including a mandrel, a supporting ring thereon, a cup of flexible material slidable on said mandrel and adapted to seat on said ring, said ring having a V-shaped groove therein to receive the lower end of said cup, thus acting to expand said cup as it moves into its seat.
8. A swab including a mandrel, a supporting ring thereon, a cup of flexible material slidable on said mandrel and adapted to seat on said ring, said ring having a V-shaped groove therein to receive the lower end of said cup, thus acting to expand said cup as it moves its seat, and means to limit the upward movement of said cup.
9. A swab including a mandrel, a supporting ring having a V-shaped groove therein, the inner wall of which is tapered upwardly, a cup of flexible material adapted to fit said seat, said cup having a limited longitudinal movement on said mandrel and adapted to be expanded by said tapered wall, and means to limit the outward movement of the upper end of said cup.
10. A swab including a mandrel, a supporting ring having a V-shaped groove therein, the inner wall of which is tapered upwardly, a cup of flexible material adapted to fit said seat, said cup having a limited longitudinal movement on said mandrel and adapted to be expanded by said tapered wall, and a plate acting to limit the upward and the outward movement of the upper end of said cup.
11. A swab for wells adapted to be raised and lowered thru a well casing, including in combination a mandrel, a flexible sleeve slidably on said mandrel, and a tapered face arranged to engage said sleeve whereby said sleeve may be expanded on downward movement and contracted on upward movement of said sleeve relative to said mandrel.
12. In a swab, a cylindrical mandrel, a pair of ring members thereon, a resilient sleeve slidably retained between said members, and means on one of said members to expand said sleeve upon its downward movement, relative to said members.
13. A swab having a mandrel, a cup slidably mounted on said mandrel, ring members to support the upper and lower ends of said cup, a tapered surface on one of said rings whereby said cup may contract to a diameter less than said members upon upward sliding movement thereof.
14. A swab including a mandrel, a slidable cup mounted thereon, means to limit the sliding movement of said cup, passages thru said mandrel to the interior of said cup, and means carried by said mandrel to prevent the downward flow of fluid thru said passages, whereby said cup may be expanded.
- In testimony whereof I hereunto affix my signature this 25th day of April, A. D. 1929.
